(57) **CLAIM**

The ornamental design for a plug mount for a video camera, as shown and described.

DESCRIPTION

FIG. 1 is a rear perspective view of a first embodiment of a plug mount for a video camera showing our new design; FIG. 2 is a front perspective view thereof; FIG. 3 is an exploded rear perspective view thereof; FIG. 4 is an exploded front perspective view thereof; FIG. 5 is a front elevation view thereof; FIG. 6 is a rear elevation view thereof; FIG. 7 is a top plan view thereof; FIG. 8 is a bottom plan view thereof; FIG. 9 is a left side elevation view thereof; and FIG. 10 is a right side elevation view thereof. FIG. 11 is a rear perspective view of a second embodiment of a plug mount for a video camera showing our new design; FIG. 12 is a front perspective view thereof; FIG. 13 is an exploded rear perspective view thereof; FIG. 14 is an exploded front perspective view thereof; FIG. 15 is a front elevation view thereof; FIG. 16 is a rear elevation view thereof; FIG. 17 is a top plan view thereof; FIG. 18 is a bottom plan view thereof; FIG. 19 is a left side elevation view thereof; and, FIG. 20 is a right side elevation view thereof. The broken lines depict portions of the plug mount for a video camera in which the design is embodied that form no part of the claimed design.
